[57] CLAIM

The ornamental design for a four compartment refuse container, as shown and described.

DESCRIPTION

FIG. 1 is a top and front perspective view of a four compartment refuse showing my new design;

FIG. 2 is a front elevational view thereof;

FIG. 3 is a rear elevational view thereof;

FIG. 4 is a side elevational view thereof, the opposite side view being a mirror image of that shown;

FIG. 5 is a cross sectional view thereof taken along the lines 5—5 of FIG. 4;

FIG. 6 is a cross sectional a view thereof taken along the line 6—6 of FIG. 2; and

FIG. 7 is a top plan view thereof without the lid. The undisclosed bottom is flat and unornamented.

FIG. 1
